UNITED STATES PATENT OFFICE.

FOREST D. HARR, OF BOULDER, AND JOHN FALLON, OF FORT COLLINS, COLORADO; SAID HARR ASSIGNOR TO GUY O. RITCHESON, OF PENDLETON, OREGON.

WIRE-SPlicing-SLEEVE WRENCH.

Application filed February 18, 1926. Serial No. 89,131.

This invention relates to a novel wrench for twisting a wire splicing sleeve and the ends of the wires encased by the sleeve, and has for one of its objects to provide a strong, durable and simple wrench of this character that can be operated with the least possible interference from the block and fall used to hold the wires during the splicing operation.

With the foregoing and other objects in view, the invention consists of the novel construction, combination and arrangement of parts hereinafter fully described and claimed, and illustrated in the accompanying drawing, wherein:

15 Figure 1 is a view in side elevation of the wrench with the jaws thereof closed,

Figure 2 is a similar view with the jaws partly opened,

Figure 3 is a sectional view taken on the plane indicated by the line 3—3 of Figure 1,

20 Figure 4 is a similar view taken on the plane indicated by the line 4—4 of Figure 1, and

Figure 5 is a detail view illustrating the 25 manner in which the sleeve receiving dies are secured to the jaws of the wrench.

Corresponding and like parts are referred to in the following description, and designated in the several views of the accompanying drawing, by similar reference 30 characters.

The wrench comprises similar jaws 2 and 3 which are preferably of elongated rectangular formation and are assembled with their longitudinal edges 4 and 5, respectively, 35 in opposition. Lugs 6 are formed on the jaw 2 adjacent an end thereof and project inwardly beyond the inner edge 4 of the jaw, and lugs 7 are formed upon the jaw 3 adjacent the corresponding end of this jaw and 40 extend inwardly beyond the inner edge 5 thereof. The lugs 6 and 7 are of semi-circular formation, and the lugs of one jaw fit in semi-circular recesses in the other. A 45 bolt 8 passing through the lugs 6 and 7 pivotally connects the jaws 2 and 3. A semi-circular lug 9 extends from the inner edge 5 of the jaw 3 and occupies when the jaws are closed a recess 10 in the jaw 2 and opening out through the inner edge 4 thereof. The lugs 6 and 7 and the lug 9 are adapted 50 to prevent the jaws 2 and 3 from having any relative twisting movement when they are closed and the wrench is in use. The free

end edge of the jaw 2 is provided with a 55 T-shaped recess 11 for the reception of a correspondingly formed dog 12 pivoted as at 13 to the jaw 3. The free end edge of the jaw 3 is provided with a recess 14 for the reception of the dog 12 and said jaw is provided with a recess 15 for the reception of a spring 15^a which bears against one end of the dog 12 to yieldingly hold it in active position. The other end of the dog 12 projects beyond the inner edge 5 of the jaw 3, 60 and it is this end that occupies the recess 11 in the jaw 2. The ends of the head 12^a of the dog 12 project beyond the sides of the jaw 2 to provide finger grips by means of which the dog may be retracted when it is 65 desired to open the jaws 2 and 3 or close the same.

The jaws 2 and 3 are provided centrally between their ends with dies 16 for the reception of the splicing sleeve. The dies 75 extend in opposite directions beyond the jaws 2 and 3, and are removably secured by screws 16^a in openings 17 formed in the jaws and extend through the sides and inner edges thereof. Lugs 18 carried by the dies 16 and 80 occupying recesses 19 formed in the jaws 2 and 3 and communicating with the openings 17, hold the dies against movement laterally with respect to the jaws.

Cylindrical passages 20 are formed in the 85 jaws 2 and 3. These passages are located adjacent the outer side edges of the jaws 2 and 3 and are arranged in parallel relation to said edges and open out through the end edges of the jaws. Bayonet slots 21 90 are formed in the jaws 2 and 3 and communicate with the passages 20 and open out through the end edges of the jaws. Handle bars 22 are slidably mounted in the passages 20 and are provided with enlarged 95 terminals 23 adapted to prevent them from becoming accidentally detached from the jaws 2 and 3. The handle bars 22 may be adjusted to extend in opposite directions beyond the end edges of the jaws 2 and 3, 100 as shown in Figure 1, or adjusted to extend beyond the free end edges of the jaws, as shown in Figure 2, and are adapted to be locked in adjusted position by pins 24 carried by them adjacent their ends and adapted to be removably engaged with the bayonet slots 21.

In practice, when it is desired to apply

the wrench to a sleeve mounted on the ends of the wires to be spliced, the handle bars 22 are adjusted to extend beyond the free end edges of the jaws 2 and 3, and therefore after the dog 12 is retracted to permit the jaws to be swung into opened position. The wrench is then applied to the sleeve and the jaws 2 and 3 swung into closed position by the handle bars 22 and locked in this position by the dog 12. The wrench is now turned to twist the sleeve and the ends of the wires, and during this operation the handle bars 22 are alternately adjusted to project beyond opposite end edges of the jaws 2 and 3 so as to clear the block and fall by which the wires are held. As the dies 16 are removably secured to the jaws 2 and 3, the wrench can be equipped with dies having active faces of the size necessary to effectively twist the sleeve used.

It should be understood that the drawing is merely illustrative and does not pretend to give exact proportions. Furthermore, the said drawing is illustrative of a preferred construction, it being our expectation that various changes and modifications may be made without departing from the spirit and scope of the invention.

What is claimed is:—

30 1. A wrench of the character set forth, comprising jaws, handle bars, and means adjustably connecting the handle bars to the jaws to permit the handle bars to be ex-

tended in the same or in opposite directions beyond the jaws.

2. A wrench of the character set forth, comprising jaws, handle bars, means adjustably connecting the handle bars to the jaws to permit the handle bars to be extended in the same or in opposite directions beyond the jaws, and means adapted to secure the handle bars in adjusted position with respect to the jaws.

3. A wrench of the character set forth, comprising pivotally connected jaws provided with passages arranged at right angles to their pivots, and handle bars adjustably mounted in the passages to permit them to be extended in the same or in opposite directions beyond the jaws.

4. A wrench of the character set forth, comprising jaws provided with parallel passages and with bayonet slots at the ends of the passages, handle bars slidably mounted in the passages to permit them to be adjusted in the same or in opposite directions with respect to the jaws, and pins carried by the handle bars and adapted to be engaged with the slots to secure the handle bars against casual movement with respect to the jaws.

In testimony whereof we affix our signatures.

FOREST D. HARR.
JOHN FALLON.
